UNITED STATES PATENT OFFICE.

HENRY WAGNER DE JARRETTE, OF DES MOINES, IOWA.

SLIP-SHEETING DEVICE.

Application filed June 15, 1925. Serial No. 37,234.

To all whom it may concern:

Be it known that I, HENRY W. DE JARRETTE, a citizen of the United States, and a resident of Des Moines, in the county of Polk and State of Iowa, have invented a certain new and useful Slip-Sheeting Device, of which the following is a specification.

The object of my invention is to provide a slip sheeting device of simple, durable and inexpensive construction.

In printing presses where color work is done, difficulty is encountered on account of the fact that the colored sheets do not dry quickly enough to prevent smearing the ink from the printed sheet to the sheet next thereunder.

In order to prevent such smearing of the ink and the offsetting thereof from one sheet to another, it is a common practice to place between the successive printed sheets other sheets called "slip sheets."

It is a difficult and slow process to insert the slip sheets between the successive printed sheets.

The purpose of my invention is to provide a device which can be used as an attachment to printing machines, which will automatically insert the slip sheets between the successive printed sheets after the printing operation.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Figure 1 shows a top or plan view of a portion of a printing machine equipped with a slip sheeting device embodying my invention.

Figure 2 is an enlarged, detail, sectional view taken on the line 2-2 of Figure 1.

Figure 3 is a similar view showing the parts in another position in the second stage of the operation.

Figure 4 is a similar view showing the parts at the next successive stage of operation.

Figure 5 is another similar view illustrating

the parts in the next or fourth stage of the operation.

Figure 6 is a similar view showing the parts in the fifth stage of operation.

Figure 7 is a detail, sectional view taken on the line 7-7 of Figure 2.

Figure 8 is a detail, sectional view taken on the line 8-8 of Figure 1.

Figure 9 is a similar view taken on the line 9-9 of Figure 1.

Figure 10 is a similar view taken on the line 10-10 of Figure 1.

Figure 11 is a similar view taken on the line 11-11 of Figure 1.

Figure 12 is a detail, sectional view taken on the line 12-12 of Figure 1 looking in the direction indicated by the arrows on the section line.

Figure 13 is a view similar to that shown in Figure 12 showing the parts in another position; and

Figure 14 is a detail, sectional view taken on the line 14-14 of Figure 12.

I have shown a very small part of the press in the present case because the press forms no part of my present invention and to show the parts thereof would detract from clearness in the illustration of the apparatus.

I have shown in Figure 2 of the drawings part of the supporting frame of the press as indicated by the reference character 10 and in Figures 1 and 2, I have shown certain frame members, such for instance as the parallel spaced frame bars 11 and below them the parallel spaced frame bars 12.

Arranged to travel on the frame members 11 are carriages 13, which have flanged wheels 19 supported on the frame members 11. The carriages 13 are connected by a fixed shaft 20, a rock shaft 21 and a rock shaft 22. The rock shaft 22 is supported in the following manner:

Near each end of the fixed shaft 20, a plate 23 is fixed thereto by means of a set screw 24. The rock shaft 22 hangs in the lower part of the plates 23.

Fixed to the shaft 20 are spaced fly sticks 25, which reciprocate lengthwise in the machine and support the printed sheets of paper.

The carriages 13 and the fly sticks 25 are

reciprocated in the machine by means of actuating arms 26 shown in Figures 1 and 2 for instance for sliding the carriages 13 backwardly and forwardly on the frame members 11 over a receiving device 27, part of which is illustrated in Figure 6.

A sheet of paper 28 is placed on the fly sticks when they are in their right-hand position as illustrated in Figures 1 and 2, and

- 10 thereupon the machine operates to move the carriages and fly sticks to the left until the fly sticks are above the receiver 27, then the fly sticks are moved back again with a quick movement which withdraws them from under the sheet of paper and drops the paper into the receiving member 27 upon a platform, which is usually of the type that automatically moves downwardly under the supply of paper.
- 15 20 On the opposite side of the receiving member 27 from that where the paper is received from the fly sticks is an inclined platform 29 upon which may rest sheets of paper, such for instance as slip sheets 30.
- 25 30 Sometimes the slip sheets are fed by hand above each printed sheet dropped into the receiver 27.

The parts heretofore described are standard printing machine parts and in themselves are not the invention which is the subject of this application.

Extending from the rock shaft 21 on the ordinary machine are fingers 30^a, which when the fly sticks 25 are at their right-hand limit of movement extend downwardly adjacent to the ends of the fly sticks 25 for serving as stops to limit the sliding movement of the paper 28 on the fly sticks.

40 The ordinary machines are provided with mechanism not here shown for rocking the shaft 21 just as the fly sticks reach their left-hand limit of movement for swinging the fingers 30^a to their position shown for instance in Figure 4 in order to let the paper 28 slide off the fly sticks 25 when the latter are withdrawn.

It is my purpose to provide in connection with the standard machine parts already described certain means whereby when a sheet of paper has been carried by the fly sticks to position above the receiver 27, that sheet of paper is gripped by the edge and held during the withdrawal of the fly sticks, and to provide further means operating with 55 the carriages for gripping a slip sheet and carrying it under the printed sheet during the return movement of the carriages and fly sticks.

Such mechanism, I will now describe.

60 Supported by means of suitable brackets 31 approximately above the delivery end of the platform 29 is a fixed shaft 32 and above it a rock shaft 33. Fixed on the shaft 32 as by set screws 34 are gripping fingers 35 having inset in their projecting upper faces

rubber strips or the like 36 for better gripping of the sheets of paper.

Fixed on the rock shaft 33 by means of set screws 37 are coating gripping fingers 38.

For actuating the fingers 38 to cause them to grip the sheets 28 between them and the fingers 35, I have provided the following means:

At one end of the shafts 32 and 33, a plate 39 is mounted thereon. Adjacent to the plate 39, a bracket arm 40 is fixed to the shaft 33 by means of a set screw 41. A cam plate 42 is pivoted as at 43 on the plate 39. The cam plate 42 is of such shape that when in one position of its pivotal movement, its face 42^a engages one side of the arm 40 as shown in Figure 13.

A spring 44 secured to the arm 40 and to the shaft 43 for the cam plate 42 tends to pull the arm 40 downwardly, so that when the cam plate 42 is in the position shown in Figure 13, the spring will pull the arm 40 to its downward limit of movement and in that position of the arm 40, the shaft 33 will have been rocked to cause the fingers 38 to have a gripping engagement with the fingers 35.

When the cam plate 42 is rocked from its position shown in Figure 13 to its position shown in Figure 12, the point 42^b of the cam plate will engage the under-surface of the arm 40 for rocking it upwardly and thus rocking the shaft 33 for moving the fingers 38 from their position shown in Figure 5 for example to their position shown in Figure 6.

At the beginning of the operation of the machine, the fingers 38 stand in their position shown in Figures 2 and 6, and the cam plate 42 stands in the position shown in Figure 12.

The arrangement of the spring 44 is such that when the cam plate is in the position shown in Figure 12, the spring tends to hold it in that position, whereas when the cam plate moves to its position shown in Figure 13, the spring tends to hold it in that position.

For moving the cam plate from the position shown in Figure 12 to the position shown in Figure 13, when a sheet of paper has been carried by the fly sticks to position above the receiver 27, I provide the following mechanism:

Pivoted as at 45 to the cam plate 42 is an upright extension 46 on a rod 47, which extends alongside the frame member 11 as shown in Figures 12 and 13 through a guide member 48 shown in Fig. 1.

Supported on one of the frame members 11 so as to be adjacent to the shaft 20 at its starting position is a bracket 49 on which is pivoted as at 50, an arm 51 having the cam faces 51^a and 51^b as shown in Figure 13.

A bearing block 52 receives the free end 130

of the rod 47 slidably as shown in Figure 14. A set screw 53 is mounted in the bearing block 52 for locking the rod 47 therein. The bearing block 52 has formed thereon a spindle 54 projected through a suitable opening in the arm 51 and having a head 55 countersunk and riveted so as to allow some rotary movement of the block 52 relative to the arm 51.

- 10 On the shaft 20 in line between the cam plate 42 and the arm 51 is fixed an actuating member 56 having converging inclined faces 56^a and 56^b. A pin 57 projects from the face 56^a as shown in Figures 12 and 13.
- 15 The parts are so arranged that the cam plate 42 stands in the position shown in Figure 12 at the commencement of an operation of the device.

When the carriages 13 and the fly sticks 20 move from their position shown in Figure 1 to their position shown for instance in Figure 3, the pin 57 engages the cam plate 42 and moves it from its position shown in Figure 12 to its positions shown in Figure 13.

The spring 44 then pulls the arm 40 downwardly, thus rocking the shaft 33 and moving the fingers 38 from their position shown in Figure 3 to their position shown in Figure 4 for gripping the edge of the sheet of paper 28.

Ordinary mechanism on the machine causes the arms 30^a to rise at substantially the same time from their position shown in Figure 3 to their position shown in Figure 4.

As the carriages 13 and the fly sticks 25 move back toward their starting position, it will be seen that the paper is pulled off the fly sticks.

40 When the carriages finish their return stroke the actuating member 56 engages the cam face 51^a of the arm 51 for actuating the rod 47 lengthwise and thus swinging the cam plate 42 from its position shown in Figure 13 to its position shown in Figure 12. This raises the fingers 38 from their position shown for instance in Figure 4 to their position shown in Figure 6.

For holding the sheet of paper taut during the return movement of the fly sticks, mounted on the rock shaft 21 are arms 58 carrying rollers 59, which when the shaft 21 is rocked for raising the fingers 30^a from position shown in Figure 3 to the position shown in Figure 4, drop downwardly to grip the paper 28 between them and certain of the fly sticks 25.

During the return movement of the fly sticks, the rollers 59 engage the paper 28 and hold it substantially taut.

For pulling a slip sheet 30 underneath the sheet of paper 28 gripped by the fingers 38 and 35, the following mechanism is provided.

On the shaft 20 are fixed fingers 60. On the shaft 22 are fixed fingers 61 to coact with the fingers 60. A bar or arm 62 is fixed on the shaft 22 as shown in Figures 1 and 8 and projects both forwardly and rearwardly therefrom.

What may be called the forward end of the arm 62 has connected therewith a spring 63, which is also connected with the plate 23 for normally holding the shaft 22 in such position that the fingers 61 are held in engagement with the fingers 60.

On the oppositely projecting end of the arm 62 from the end to which the spring 63 is attached is a pin 64.

Hung on one of the bars 12 is a channel-shaped member 65, which may be adjustably fixed on the members 12 in different positions by means of the set screw 66.

Pivoted to the upper forward corner on the inside of the support 65 is a cam strip 66 or the like 66, which at its other end has a pin 67 traveling in a curved slot 68 in the support 65.

Normally the rear end of the cam strip 66 is at the bottom of the slot 68.

The parts are so arranged that the strip 66 is in the path of the travel of the pin 64 during the reciprocation of the carriages 13. They are also so arranged that when the carriages move from their position shown in Figure 2 for moving the fly sticks to the position shown for instance in Figure 3, the pin 64 will engage and travel upwardly on the strip 66 for thus rocking the shaft 22 and opening the fingers 61 as illustrated in Figure 3.

This movement is arranged for in order that a slip sheet 30 which has been fed rearwardly in the machine may have its rearward edge in position to be gripped between the fingers 60 and 61 when the pin 64 clears the cam strip 66.

On one of the frame members 12 is another channel-shaped member 65^a similar to the member 65 having thereon a similarly pivoted cam strip 66^a, which, however, is pivoted at its rearward end to the upper rearward part of the member 65^a and has its pin and slot connection with the forward end of the member 65^a similar to that of the cam strip 66.

On the rearward movement of the carriages 13, the pin 64 passes under the cam strip 66 and raises its free end without rocking the shaft 22, but rides up the cam strip 66^a to open the fingers 66 and release the slip sheet, after which the pin 64 clears the rearward end of the strip 66^a, and the spring 63 actuates the arm 62 for rocking the shaft 22 and closing the fingers 61.

For holding the slip sheet taut, while it is being drawn rearwardly by the fingers 60 and 61, there are pivoted on the shaft 32

arms 69 on which are rollers 70. The arms 69 have curved extensions 71 (see Figure 10) arranged to coact with cam discs 72 having notches 73 and arranged on the rock shaft 33.

- 5 The parts just described are so arranged that when the shaft 33 is rocked to position for holding the fingers 38 in open position, the extensions 71 are engaged by such portions of the cams 72 on the shaft 33 as to cause the rollers 70 to be held up as shown in Figure 10.

When, however, the shaft 33 is rocked for closing the fingers 38, the notches 73 are moved to position to receive the ends of the curved extensions 71 and permit the rollers 70 to drop downwardly upon the slip sheets 30.

For further facilitating the accuracy and efficiency of the machine, there is provided 20 supported on the frame members just below the discharge end of the platform 29, a transverse shaft 74 on which a projecting finger 75 is fixed by means of a set screw 76. The finger 75 is connected by means 25 of a spring 77 with an arm 78 fixed on the shaft 32.

On the rock shaft 33 is an arm 79 pivoted to which is a rod 80 extended loosely through a guide opening 81 in the arm 78 and resting adjacent to the finger 75 when the fingers 38 are open.

On the rod 74 are fixed stop fingers 82 which when the shaft 74 is rocked to its position with the fingers 75 at their upper 35 limit of movement shown in Figure 9, project upwardly through slots 83 in the platform 29 and slightly above the platform as shown in Figures 2, 3 and 6.

The top slip sheet 30 is fed downwardly 40 and rearwardly in the machine until its rearward edge engages the stop fingers 82, as illustrated for instance in Figure 3.

When the shaft 33 is rocked for causing the fingers 38 to move for gripping the printed sheet 28 between the fingers 38 and the fingers 35, the movement of the rock shaft 33 actuates the rod 80 for pressing the finger 75 downwardly against the tension of the spring 77 and thus rocking the shaft 74 for lowering the stop fingers 82 from their position shown in Figure 3 to their position 50 illustrated in Figure 4.

This movement occurs at such a time as to permit the fingers 60 and 61 to pull the slip sheet without any interference from the stop fingers 82.

It will be understood that the various fingers are so staggered as not to interfere with each other or with the fly sticks.

60 I will now describe in greater detail and in proper sequence the operation of the machine.

When the fly sticks are in their right hand positions as shown in Figure 1 ready 65 to receive a printed sheet, the fingers 61 are

held in closed position by means of the spring 63 and the arm 62 fixed on the rock shaft 22.

The fingers 38 are held in raised position because the cam plate 42 is in its position 70 shown in Figure 12, where it is held by means of the spring 44.

The operator feeds the top slip sheet 30 from the position on top of the pile downwardly and rearwardly to its position shown 75 in Figure 3.

The operation of the machine parts not here shown advances the fly sticks from their position shown in Figure 1 to their position 80 shown in Figure 3.

The pin 64 slides under and raises the cam strip 66^a without being effected thereby.

As the fly sticks move from their position shown in Figure 2 toward position shown in Figure 3, the pin 64 slides up the cam strip 85 66, thereby rocking the shaft 22 and causing the fingers 26 to move to open position readily to receive between them and the fingers 60 the rearward edge of the top slip sheet 50.

Parts of the machine which are standard and not here shown rock the shaft 21 for lifting the fingers 30^a and lowering the rollers 59.

At the finish of the forward stroke of 95 the fly sticks, the pin 57 engages the cam plate 42 moving it from its position shown in Figure 12 to its position shown in Figure 13 for permitting the spring 44 to rock the shaft 33 for lowering the fingers 38 and causing them to grip the forward edge of the printed sheet between them and the fingers 35.

When the pin 64 clears the forward end of the strip 66, the spring 63 rocks the shaft 105 22 for moving the fingers 61 to gripping position for engaging the slip sheet.

The parts are then in the position shown in Figure 4.

The rocking of the shaft 33 for lowering 110 the fingers 38 actuates the arm 79 (see Figure 9) and the rod 80 for engaging the finger 75 and rocking the shaft 74 for lowering the stop fingers 82. The rocking of the shaft 33 also brings the cams 72 to position where the 115 slots 73 receive the curved extensions 71 on the arms 69 permitting the rollers 70 to drop by gravity.

The fly sticks then reciprocate rearwardly as shown in Figure 5 with the slip sheet 120 30 gripped between the fingers 60 and 61.

During this rearward movement of the fly sticks, the rollers 59 hold the printed sheet 28 taut and the rollers 70 hold the slip sheet taut until both sheets stand above the 125 pile D shown in Figure 6.

During the return stroke of the fly sticks, the pin 69 travels under the cam strip 66 raising its free end without interfering with or operating the shaft 22.

At the completion of the return stroke of the fly sticks, the pin 64 travels up the cam strip 66^a for thus rocking the shaft 22 against the tension of the spring 63 (see Figures 1, 2 and 8) for operating the fingers 61 (see Figure 6) and releasing the slip sheet.

The shaft 21 is rocked by the usual mechanism of the machine for lowering the fingers 30^a and correspondingly raising the rollers 59.

Likewise at the completion of the return stroke of the fly sticks, the point of the cam 56 engages the arm 51 swinging it downwardly and forwardly in the machine for moving the rod 47 lengthwise and moving the cam plate 42 from its position shown in Figure 13 to its position shown in Figure 12.

This movement of the cam plate permits the spring 44 to actuate the arm 40 for rocking the shaft 33 for raising the fingers 36 and releasing the printed sheet 28.

The same movement of the shaft 33 brings the cams 72 to position for so engaging the extensions 71 as to raise the rollers 70. (See Figure 10.)

The same movement of the shaft 73 also raises the arms 79 and the rods 80 for permitting the spring 77 to raise the arm 75 and thus rock the shaft 74 for moving the stop fingers 82 from their position illustrated in Figure 5 to their position shown in Figure 6.

The machine is then ready for another operation.

I might say that I have connected the shafts 20 and 22 by links 83 for preventing their spreading.

The shafts 33 and 32 are connected by similar links 84 (see Figure 1) for preventing their spreading.

It will be seen from the foregoing that the present slip sheeting device provides an attachment for the standard printing machine, whereby the printed sheet instead of being simply dropped when the fly sticks slide rearwardly with a quick movement is gripped at their forward ends and are held by the rollers 59 engaged with the fly sticks, so as to be held taut during the return movement of the fly sticks.

The slip sheet is engaged by fingers carried by the shaft 20 and 22 and drawn to position below the printed sheet and above the pile D.

In order to prevent the slip sheet from dragging over the top sheet on the pile, the rollers 70 engage the moving slip sheet and hold it taut. Thus there is no dragging movement of or on the printed sheets which would tend to smear the ink thereon.

Both the printed sheets and the slip sheets are held taut until they are dropped and permitted to rest on the pile D with the

danger of smearing the ink reduced to a minimum.

Some changes may be made in the details of the structure of my slip sheeting device without any departure from the real spirit and purpose of my invention, and it is my intention to cover by my claims any such changes or modifications in structure and any use of mechanical equivalents, which may be included within the real scope of my invention and of my claims.

I claim as my invention:

1. In a machine of the class described, the combination of means for advancing a printed sheet to a predetermined position and to then return to starting position, and means for gripping one edge of the sheet when it reaches such predetermined position, and for holding it during the return movement of said first means.

2. In a machine of the class described, the combination of means for advancing a printed sheet to a predetermined position and to then return to starting position, and means for gripping one edge of the sheet when it reaches such predetermined position and for holding it during the return movement of said first means, and means for holding such sheet taut during such return movement.

3. In a machine of the class described, the combination of means for advancing a printed sheet to a predetermined position and to then return to starting position, means for gripping one edge of the sheet when it reaches such predetermined position and for holding it during the return movement of said first means, and means for releasing the gripping means at the completion of such return movement.

4. In a machine of the class described, the combination of means for advancing a printed sheet to a predetermined position and to then return to starting position, and means for gripping one edge of the sheet when it reaches such predetermined position and for holding it during the return movement of said first means, means for holding such sheet taut during such return movement, and means for releasing the gripping means at the completion of such return movement.

5. In a machine of the class described, the combination of means for advancing a printed sheet to a predetermined position and to then return to starting position, means for gripping one edge of the sheet when it reaches such predetermined position and for holding it during the return movement of said first means, and means carried by said first means for drawing a slip sheet under the printed sheet on such return movement.

6. In a slip sheeting device, means for

moving a printed sheet to a predetermined position, and means carried by said first means for moving a slip sheet to position substantially below the first sheet.

5 7. In a slip sheeting device, means for moving a printed sheet to a predetermined position, and means actuated by the movement of said first means for moving a slip sheet to position substantially below the first sheet.

10 8. In a machine of the class described, means for moving a printed sheet to a predetermined position, means for holding the sheet in such position, and means for moving a slip sheet spaced from the first sheet to position substantially below the first sheet.

15 9. In a slip sheeting device, means for moving a printed sheet to a predetermined position, means for holding the sheet in such position, and means comprising gripping fingers for moving a slip sheet to position substantially below the first sheet.

20 10. In a slip sheeting device, means for moving a printed sheet to a predetermined position, means for holding the sheet in such position, and means comprising gripping fingers and means engaging the printed sheet against said first means for moving a slip sheet to position substantially below the first sheet.

25 11. In a slip sheeting device, means for moving a printed sheet to a predetermined position, means actuated from said first means for holding the sheet in such position, and means for moving a slip sheet to position substantially below the first sheet.

30 12. In a slip sheeting device, means for moving a printed sheet to a predetermined position, means comprising gripping fingers actuated from said first means for holding the sheet in such position, and means for moving a slip sheet to position substantially below the first sheet.

35 45 13. In a machine of the class described, the combination of means for advancing a printed sheet to a predetermined position and to then return to starting position, means for gripping one edge of the sheet

when it reaches such predetermined position 50 and for holding it during the return movement of said first means, and means for releasing the gripping means at the completion of such return movement actuated from said first means.

55 14. In a machine of the class described, the combination of means for advancing a printed sheet to a predetermined position and to then return to starting position, means 60 for gripping and holding the sheet taut during such return movement.

65 15. In a machine of the class described, the combination of means for advancing a printed sheet to a predetermined position and to then return to starting position, means 70 for gripping and holding the sheet taut during such return movement and for then releasing it.

75 16. In a machine of the class described, the combination of means for advancing a printed sheet to a predetermined position and to then return to starting position, means 80 for gripping one edge of the sheet when it reaches such predetermined position and for holding it during the return movement of said first means, and means for drawing a slip sheet under the printed sheet on such return movement.

85 17. In a machine of the class described, the combination of means for advancing a printed sheet to a predetermined position and to then return to starting position, means 90 for gripping and holding the sheet taut during such return movement, and means for drawing a slip sheet under the printed sheet while it is so held.

95 18. In a machine of the class described, the combination of means for advancing a printed sheet to a predetermined position and to then return to starting position, means 100 for gripping and holding the sheet taut during such return movement, and means for drawing a slip sheet under the printed sheet while it is so held and for holding the slip sheet taut while it is being so drawn.

HENRY WAGNER DE JARNETTE.
